DESIGN FOR A BOXLIKE CONTAINER OR
SIMILAR ARTICLE

Herbert W. Hill, San Francisco, Calif.

Application August 27, 1947, Serial No. 141,087

Term of patent 3½ years

(Cl. D58—13)

To all whom it may concern:

Be it known that I, Herbert W. Hill, a citizen of the United States of America, residing at San Francisco, in the county of San Francisco and State of California, have invented a new, original, and ornamental Design for a Boxlike Container or Similar Article of which the following is a specification, reference being made to the accompanying drawings, forming a part thereof.

Fig. 1 is a side elevation of my boxlike container, both sides thereof being alike.

Fig. 2 is a top plan view of my boxlike container on a reduced scale, and

Fig. 3 is an end elevation of my boxlike container on a reduced scale.

I claim:

The ornamental design for a boxlike container or similar article, substantially as shown.
